Primary Examiner — Susan Moon Lee

(74) Attorney, Agent, or Firm — Greer, Burns & Crain, Ltd.

(57) **CLAIM**

We claim the ornamental design for an animal training collar device, as shown and described.

DESCRIPTION

FIG. 1 is a perspective view of an animal training collar device showing my own design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the animal training collar device, shown in use.

The elements in broken line are not claimed.
